UNITED STATES PATENT OFFICE.

JULES LINDAUER, OF PARIS, FRANCE.

CORSET BELT.

Application filed June 23, 1920. Serial No. 391,124.

To all whom it may concern:

Be it known that I, JULES LINDAUER, citizen of the Republic of France, residing at 42 Faubourg du Temple, Paris, in the Republic of France, have invented new and useful Improvements in Corset Belts, of which the following is a specification.

The height of the front of corset belts tends to cause the flesh to overhang in the 10 region of the diaphragm and frequently occasions a serious inconvenience there, when the wearer stoops down and even when she simply sits down.

The present invention consists in providing these corset belts with a support formed of a transverse band lightly stiffened or boned and intended to be placed under the end of the top of the front of the corset to which it is preferably attached 20 lightly so as to be able to be stretched independently of the top of the corset, the said support either forming or not forming an integral part of the corset.

This support lightly supports the body 25 above the waist up to about the base of the chest without interfering with respiration which must remain free and it also prevents the top of the belt (that is to say the part where the belt terminates in front) 30 from bearing on the flesh and causing it to overhang. The said support has also the effect of diminishing the excessive pressure of the top of the corset at a very sensitive point where it would cause a serious inconvenience. 35

The accompanying drawing shows by way of example a method of carrying out the invention.

In this drawing:—

40 Figure 1 shows a support for a corset belt, on the bust of a woman seen from the front.

Figure 2 shows the same support in section on the bust of a woman seen from the 45 side the thicknesses being exaggerated in the drawing for the sake of clearness.

Figure 3 is a detail view of the said support.

As shown in the drawing, the support 1, 50 which forms the subject matter of this invention is intended to be placed behind the front 2 of the corset, that is to say, internally, projecting beyond its upper edge 3 and is stretched there lightly by two ends 55 of elastic ribbon 4 and 5 each provided with a hook 6 and fixed internally on the right

and left on the corset at a suitable distance, while a small string 7 placed at about the middle of the support and preferably inside the corset connects the said support 60 with the corset but leaves a little play so as to act as a hinge and in such a way as to prevent the support from coming down.

This semi-rigid support is made of fabric (preferably of a fabric like that of which 65 the corset is made) may be ornamented with lace, embroidery, etc. and trimmed with plush. It is of suitable shape and slightly stiffened by a boning 8, the bones being placed preferably in a horizontal direction: 70 it may however be sometimes useful for it to have some bones in a vertical direction in order to avoid the collapse of the article vertically. It forms also at each of its ends a tab 9 provided with a series of eyelets 10 75 into each of which hooks one of the two hooks 6, each carried by the extensible end or tab of ribbon 4 or 5, fixed preferably by stitching 11 to the inside of the corset by its opposite end to that which carries the hook 80 6. The point at which this tab is placed in the corset varies according as the height of the front of the corset differs more or less from the height of the side of the corset and according to the length of the support. 85 Each of these elastic ribbons 4 or 5 will however be fixed towards the point of the dress preserver and at a suitable place so that its middle may be in line with one of the eyelets of the corresponding tab of the support. 90

In corset belts which do not open down the front, i. e. which are not fastened together having neither a busk or other closing device in place of it, the support may be 95 held together without the use of hooks and eyelets, being simply fixed then by two small rubber bands at the ends and held towards the middle by a small string attached to the corset so as to leave a slight amount of 100 play.

It must be quite understood that support for corset belts may be considered as an integral part of the corsets in manufacture or may be considered as an independent article 105 to be fixed to all types of corsets already manufactured and in use.

Having now described my invention, what I claim as new and desire to secure by Letters Patent is:

1. A protector for corset belts comprising a transverse band lightly boned and

adapted to be placed interiorly of the corset between the upper front edge of the corset and the body of the wearer, means on the ends of said band for fastening the same to the corset and a flexible tab secured to the middle part of said band and adapted to loosely connect said middle part to the corset.

2. A protector for corset belts comprising a transverse band lightly boned and adapted to be placed interiorly of the corset between the upper front edge of the corset and the body of the wearer and elastic ribbons secured to the ends of said band and adapted to be secured to the corset and a flexible tab secured to the middle part of said band and adapted to loosely connect said middle part to the corset.

3. A corset belt comprising a corset belt body, a transverse band lightly boned and adapted to be placed interiorly of the corset between the upper front edge of the corset body and the body of the wearer, elastic ribbons secured to the corset, hooks on the inner free ends of said ribbons, and eyelets on the

ends of the transverse band and adapted to engage with said hooks.

4. A corset belt comprising a corset belt body, a transverse band lightly boned and adapted to be placed interiorly of the corset between the upper front edge of the corset body and the body of the wearer, elastic means connecting the opposite ends of the transverse band to the corset and a flexible tab loosely connecting the middle part of the transverse band to the corset.

5. A corset belt comprising a corset belt body, a transverse band lightly boned and adapted to be placed interiorly of the corset between the upper front edge of the corset body and the body of the wearer, elastic ribbons secured to the corset, hooks on the inner free ends of said ribbons, eyelets on the ends of the transverse band and adapted to engage with said hooks and a flexible tab loosely connecting the middle part of the transverse band to the corset.

In testimony whereof I have signed my name to this specification.

JULES LINDAUER.
